UNITED STATES PATENT OFFICE.

JOHN GROSS AND AARON RUTH, OF DECATUR, ILLINOIS.

DESIGN FOR CASE FOR RIBBONS, LACES, VELVETS, &c.

Specification forming part of Design No. 5,975, dated July 9, 1872.

Specification describing a Design for a Case for Ribbons, Velvets, Laces, Cords, &c., invented by JOHN GROSS and AARON RUTH, of Decatur, in the county of Macon and State of Illinois.

The nature of our design is fully represented in the accompanying drawing, to which reference is made.

Figure 1 is a perspective view of the case and embodies our invention, and Fig. 2 is a vertical transverse section of the same.

A A are the ends of the case; B B', the sides; b, a hinged door in the front side B. The top of the case is an octagon shape, as shown at C C'. The door b, top D, and at C C', are glazed. The door, top, side B, and at C C', are ornamented with gothic panels, as shown at a a.

The case can all be made of the same kind of wood, or the paneling of different-grained woods.

The interior of the case is provided with spools operated by certain devices, which it is not necessary to mention in this application.

We are aware that rectangular cases have been made for ribbons, &c., and that a showcase has been made with the front at an acute angle with the bottom of the case, and these we do not claim. The distinctive character of our design is in the octagon-shape of the top of the case.

What we claim as our invention is—

A design for a case for ribbons, velvets, laces, cords, &c., with the octagon-shaped top, as shown at C C', and with or without the gothic panels a a, substantially as above described.

JOHN GROSS.
AARON RUTH.
